2 Sheets-Sheet 2

UNITED STATES PATENT OFFICE

GEORGE C. BISHOP, OF GARDEN CITY, NEW YORK

METAL DOOR

Application filed June 27, 1927. Serial No. 201,733.

Reference is had to the accompanying drawings which illustrate the preferred form of the invention, though it is to be understood that the invention is not limited to the exact details of construction shown and described, as it is obvious that various modifications thereof within the scope of the claims will occur to persons skilled in the art.

In said drawings:

10 Fig. 1 is a view in elevation of a metal door constructed in accordance with this invention;

Fig. 2 is a broken vertical section taken on the line 2—2 of Fig. 1;

15 Fig. 3 is a broken horizontal section taken on the line 3—3 of Fig. 1;

Fig. 4 is a fragmentary view in elevation drawn to a larger scale and showing a corner formed by the top rail and one of the stiles;

20 Fig. 5 is a vertical section taken on the line 5—5 of Fig. 4;

Fig. 6 is a view similar to Fig. 4 showing a corner formed by the bottom rail and one of the stiles;

25 Fig. 7 is a horizontal section taken on line 7—7 of Fig. 6; and

Figs. 8 and 9 are fragmentary sections taken on the lines 8—8 and 9—9 respectively, of Fig. 1.

30 It is an object of this invention to provide a metal door of simple and rugged construction which may be readily and economically manufactured.

As shown in the drawings, a door constructed in accordance with this invention comprises a metal sheet or plate 1 provided at its edges with top and bottom rails 2 and 4 respectively, and stiles 6 and 8. Each of the stiles and rails is formed of a single metal sheet bent to a rectangular shape to provide integral structures having side portions 10, outer edge portions 12 and inner edge portions 13 and 14 on which are formed inwardly projecting flanges 15 and 16, respectively, which engage on opposite sides of sheet 1 and are secured thereto by rivets 18. The meeting ends of the stiles and rails are mitred as at 19 and are secured together by welding along the seam or in any suitable manner and by being riveted to spacing or filler blocks 20 which are

inserted into the corners. The filler blocks 20 are formed with oppositely disposed depressed portions 21 to which the stiles and rails are fitted so as to interlock therewith and through which the riveting is effected as by rivets 17.

The upper rail 2 is reinforced by an angle 22 which engages the outer edge portion 12 and one of the side portions 10 of the rail, and extends between the filler blocks inside of the rail. The flange 23 of the angle 22 which contacts with a side portion 10 of the rail overlaps the filler blocks as at 24 and is secured thereto by screws 26 which extend through the filler blocks, the flange of the angle 22 and through the side portions 10 of the rail 2. Screws 28 which secure the angle 22 to the side portion 10 of the rail also secure a flat hanger plate 30 to the outside of the side portion 10 which is engaged by the angle 22, the hanger plate 30 projecting above the door edge and having the hanger brackets (not shown) secured thereto. The outer edge portion of the bottom rail 4 is reinforced by a channel 32 which extends from side to side of the door within the rail and beneath the filler blocks 20, the filler blocks being spaced from the bottom edge of the door for this purpose. Screws 34 which secure the channel 32 in position also secure a Z-shaped guide plate 35 which engages one side and the outer edge portion of the rail and has a flange 37 projecting outwardly from the door edge to form a guide flange.

The stiles 6 and 8 are provided with reinforcing channels 36 and 38, respectively, which extend within the respective stiles from the outer edge portion of the top rail 2 to the top of the reinforcing channel 32 in the bottom rail 4, the filler blocks 20 having their edges reduced in thickness as at 39 so as to fit between the flanges of the channels 36 and 38. Screws 40 secure the channels to the edge portions of the stiles and filler blocks. To the edge of the stile 8, screws 43 secure the rubber weather strip 42.

To form the panels, pressed channel-shaped members 44 and 46, having outwardly projecting flanges 48, are secured to one side of the sheet 1 by rivets 50 so as to form a center

rail which extends between the stiles 6 and 8 and a center stile which extends from the bottom rail 4 to the rail formed by the member 44. Where the member 44 engages with the stiles 6 and 8, the flanges 48 are cut away so as to permit the flanges 48 to abut against the flanges of the stiles and permit the channel portion of the member 44 to engage the inner edge portions of the stiles. The member 44 is secured to the stiles 6 and 8 by welding along the seams and by rivets 51 which replace the rivets in the flanges of the stiles and extend through the web portion 53 of the channel and through spacing blocks between the web and the flanges of the stiles. Where the member 46 engages with the rail 4 and the rail formed by the member 44, its flanges 48 are cut away to permit the flanges and channel portion to abut the rails in the same manner as the member 44 engages the stiles, and the member 46 is secured in the same manner as the member 44.

In the upper panel formed in sheet 1, two rectangular openings are formed by punching to receive the glass panels 70, Z-shaped framing strips 52 being secured about the openings to one side of sheet 1 by rivets 54, while glass retaining strips 56 are secured about the openings on the other side of sheet 1 by screws 58. To the stile 6 are secured the handles 60 and 62 by means of rivets or bolts 64 which extend through the openings in the handle and through the filler blocks 20, 66 and 67 secured in the stile. To provide for securing the door, the eye 68 for a door securing hasp is secured to the stile at the filler block 67.

What is claimed is:

1. A metal door comprising a single plate, 40 stiles and rails secured to the edges of said plate, filler blocks at the corners of said plate, stiles and rails, said filler blocks, stiles and rails having depressions at the corners and means in said depressions securing said stiles 45 and rails to said filler blocks, said securing means projecting beyond the surfaces of said depressions and lying within the normal planes of the sides of the stiles and rails.

2. A metal door comprising a single plate, 50 stiles and rails secured to the edges of said plate, recessed filler blocks at the corners and serving to unite said stiles and rails and reinforcements in said stiles fitting the recesses in said filler blocks.

55 3. A metal door comprising a single plate, stiles and rails secured to the edges of said plate, filler blocks at the corners and serving to unite said stiles and rails and reinforcements in said stiles overlapping said filler blocks, said filler blocks having reduced portions receiving said reinforcements.

4. A metal door comprising a single plate, stiles and rails secured to the edges of said plate, filler blocks at the corners of said plate, 65 stiles and rails, said filler blocks having de-

pressions in the sides thereof and said stiles and rails fitting in said depressions, and means in said depressions securing said stiles and rails to said filler blocks.

5. A metal door comprising a single plate, 70 stiles and rails secured to the edges of said plate, filler blocks at the corners serving to unite said stiles and rails, and channel reinforcing means in said stiles, said filler blocks having reduced edges receiving the flanges of 75 said channels.

In witness whereof I have hereunto set my hand.

GEORGE C. BISHOP.
